UNITED STATES PATENT OFFICE.

CHARLES W. IDEN, OF NEW YORK, N. Y., ASSIGNOR TO THE ELECTRO LAMP COMPANY, OF WEST VIRGINIA.

DESIGN FOR A LAMP.

SPECIFICATION forming part of Design No. 28,844, dated June 14, 1898.

Application filed March 23, 1898. Serial No. 674,945. Term of patent 14 years.

To all whom it may concern:

Be it known that I, CHARLES W. IDEN, a citizen of the United States, residing at New York, in the county and State of New York, have invented and produced a new and original Design for Lamps, of which the following is a specification, reference being had to the accompanying drawings.

Figure 1 is a side elevation of a lamp, showing my new design. Fig. 2 is a rear elevation thereof.

As shown in the drawings, the leading or material feature of my design consists of the hexagonal conical shells A B, placed end to end and having a line of beading II, surrounding the meeting line of the two parts, the hexagonal conical shell C, the lower ends of the panels of which are curved, the cylinder D, the hexagonal half-ball shell E, provided with the beading F at its outer edge, and the supporting bar or rod G.

The shells A and B are surmounted on the shell C, and the shell C surmounted on the cylinder D, which serves as a base for the lamp. The supporting bar or rod G is ornamented with scrolls G', and its middle ornamental portion I unites the shells B and C. 25

Having thus described my invention, what I claim as new, and desire to secure by Letters Patent, is—

The design for a lamp, substantially as shown and described.

In testimony whereof I have signed my name to this specification in the presence of two subscribing witnesses.

CHARLES W. IDEN.

Witnesses:

W. LAIRD GOLDSBOROUGH,
GEO. E. CRUSE.
